UNITED STATES PATENT OFFICE

2,279,853

PORTABLE HOIST

Fred L. White, Marion, Ohio, assignor to The Osgood Company, Marion, Ohio, a corporation of Ohio

Application June 17, 1940, Serial No. 340,881

7 Claims. (Cl. 254—176)

This invention relates to portable material handling devices and is more particularly directed to a device for positively drawing the cable from the winding reel or drum by taking up the slack as the cable is being unwound.

The object of this invention is to provide a mechanism in a material handling device adapted to positively withdraw the cable as it is unwound from the winding reel or drum and pass it over the boom sheave.

Another object of this invention is to prevent an unwound cable from piling near the winding drum or reel on the platform and boom of a portable hoist and thereby requiring excessively hard labor to withdraw it over the boom sheave.

Another object of the invention is to prevent the snagging and kinking of the hoist cable on the boom of the hoist.

A still further object of the invention is to provide a throwout device or slack puller on the boom of a portable hoist to positively draw unwound hoist cable away from the reel or winding drum and out over the boom sheave.

Another and still further object of the invention is to provide a means on a material handling device which operates in synchronism with the cable reel or drum to maintain a taut condition in the hoist cable between said means and the reel.

Other and further objects of the invention will appear to those skilled in the art to which this invention pertains as the description proceeds which taken in connection with the accompanying drawings sets forth the preferred embodiments of the invention but it is distinctly understood that such description and disclosure is not to be taken as a limitation of the invention which is limited only by the appended claims and any and all variations, modifications and alterations of structure coming within the spirit and scope thereof are included herein.

In the drawings:

Fig. 1 shows a schematic side elevational view of a portion of a portable hoisting device.

Fig. 2 shows a plan view of the boom shown in Fig. 1.

Fig. 3 shows a side elevational view of the boom showing the driving means mounted thereon.

Fig. 4 is a sectional view of the piston and cylinder device used in Fig. 3.

Fig. 5 shows a side elevational view of a modification of the invention.

Fig. 6 shows a plan view of a section of the boom indicated by the arrowed lines of Fig. 5.

Portable crane type hoisting mechanism, drag lines and similar devices in which a cable is em-

ployed very frequently employ tools on the free end of the cable that passes over the sheave on the free end of the boom that are insufficient in weight to positively pay out the cable over the boom sheave. It has been necessary in the past to require helpers to draw the cable over the boom sheave as it is being paid out from the reel or drum. If this is not done the cable will pile up on the boom or cabin deck or platform of the hoist causing it to kink and become snagged as it is unwound from the drum. Applicant has therefore provided a throwout device or slack puller which is mounted on the boom, preferably near the sheave to positively pass the cable from said drum as it unwinds out over the boom sheave thereby obviating the necessity of a helper pulling the cable over the boom sheave as it unwinds and preventing the snagging and kinking previously described.

A preferred embodiment of the aforementioned device is more particularly set forth in Figures 1 to 4 inclusive, in which 1 indicates the operators deck or platform of a portable crane hoist and on which deck the operating mechanism for drawing in or unwinding the hoist cable is mounted. A boom 2 is tiltably mounted on the platform 1 on a pivot 3 and may be tilted by a conventional means (not shown). At the opposite end of boom 2 a sheave 4 is rotatably mounted in appropriate bearings supplied therefore and each of which constructions is also well known to the art. The hoist has a winding reel or drum 5 which is rotatably mounted on the deck or platform 1 in any well known manner. Motive power for the operation of the drum is supplied from any well known prime mover which is connected to a gear 6 preferably mounted on the pin or pivot 3. Gear 6 is connected to an idler 7 which in turn is connected to a gear or wheel 8 which rotates the winding reel or drum 5. Each of the foregoing is shown schematically to more clearly illustrate the operation.

A cable 9 is wound on the reel 5 and is led to the sheave 4 on the end of boom 2 and has an appropriate tool 10 secured thereto.

Gear 6 has a sprocket 11 integrally associated therewith which is connected to a second sprocket 12 driving a gear 13 rotatably mounted in housing 14. A sprocket chain 15 or other suitable power transmitting mechanism connects sprockets 11 and 12 to transmit rotary motion to drive gear 13. The gear-box or support 14 is mounted upon a platform 16 secured to boom 2. Gear box 14 has a second gear 17, meshing with gear 13, rotatably mounted therein to which a shaft

18 is operatively connected. Shaft 18 extends to the slack puller or throwout device 19 which is suitably mounted on a base 20 fixed to the boom 2. The shaft 18 has fixed thereto a gear 21 which engages a gear 22 secured to shaft 23 rotatably mounted in the slack puller or throwout device 19. Mounted upon the shaft 23 is a sheave 24 which is adapted to be engaged by the cable 9 by means of mechanism hereinafter set forth.

It is apparent therefore that the sheave 24 is constantly rotated. The gears driving sheave 24 and the cable or reel or drum 5 are so arranged and proportioned such that there will always be a substantial amount of tension in that portion of the cable 9 extending between the sheave 24 and the drum or reel 5. Attention is still further invited to the fact that cable 9 is only in engagement with sheave 24 when the reel 5 is paying out or unwinding cable 9.

Means have been provided to positively engage the cable 9 with the sheave 24 which comprises a sheave 25 freely rotatably mounted on a lever 26 pivotally mounted to base 20 of the throwout device 19 on pivot 27. A fluid pressure motor 28 mounted on boom 2 has its piston rod 29 connected to the free end of lever 26. Cylinder 30 is rigidly mounted on said boom 2 and piston 31, to which piston rod 29 is connected, moves relatively thereto whereby sheave 25 is vertically adjusted or moved relatively to the sheave 24. A conduit 32 is connected to the cylinder 30 for the purpose of transmitting pressure fluid thereto. An appropriate valve 33 is mounted on the deck or platform 1 to manually control the admission of pressure fluid to the motor 28. A suitable source of pressure fluid, mounted on deck 1, is provided in order to operate the motor 28. Motor 28, as will be observed, is a single acting motor. Attention is further invited to the fact that sheave 25 is disposed immediately below and in line with or in the same plane as the sheave 24 and is constantly engaged by the cable 9.

The operation of this device provides for positively taking up the cable 9 as it is unwound from the reel or drum 5. When therefore the unwinding operation is being performed the operator actuates motor 28 which urges the pivoted lever 26 upwardly thereby bringing the cable 9 in engagement with the rotating sheave 24. The frictional engagement of the cable 9 and the sheave 24 is sufficient to cause any slack occurring in cable 9 to be taken up thereby positively paying out the cable over the sheave 4 and preventing any possible kinking or snagging of the cable 9 near the drum 5 on the deck or platform 1. Persons manipulating and handling any instrumentalities adapted to be connected to tool 10 are therefore relieved of the necessity of dragging out the cable 9 and eliminating the troublesome kinks and snags that might otherwise occur.

A modification of the aforementioned structure is set forth in Figures 5 and 6 in which the basic boom 34 and platform 35 are pivotally associated one with the other. A cable winding reel or drum 36, schematically illustrated, is operatively associated therewith on which a cable 37 is wound and having an appropriate tool 38 connected thereto is led out over the sheave 39 rotatably mounted on the free end of the boom 34. A platform 40 is mounted on the boom 34 upon which an electric motor 41 is mounted. A second platform 42 is mounted on the boom 34 near the platform 40 and upon which a sheave 43 is rotatably mounted in a housing 44 on shaft 45,

suitable bearings being provided for the shaft 45. The armature shaft of motor 41 is equipped with a pulley 46 and shaft 45 has pulley 47 secured thereto. The two pulleys are connected by a belt or other power transmitting means 48.

A sheave 49 is pivotally mounted on the platform 42 in a manner similar to the mounting of sheave 25 previously described. A fluid pressure motor 50 has a conduit 51 connected thereto which in turn is connected to an appropriate valve 52 to control the admission of pressure fluid to the motor 50. The cable 37 is in constant engagement with sheave 49. Sheave 49 lies in the same plane as sheave 43 and when pressure fluid motor 50 is operated the cable 37 is brought into engagement with the sheave 43. Motor 41 may be constantly rotating or it may be rotating only at such times as when the cable 37 is being paid out but in either event the vertical movement of the sheave 49 is necessary to bring the cable 37 in engagement with the sheave 43. The operating relationship of sheave 49, cable 37 and sheave 43 is identical to that previously described in connection with Figures 1 to 4. The speed of sheave 43 is proportioned to the speed of drum 36 such that cable 37 will be in tension; i. e.; the speeds will in effect be more or less synchronized.

In those devices of the character set forth in Figures 1 to 4, wherein unusually long booms are employed, the shaft 18 may be supported or journaled at one or more intermediate points to obviate any whipping of the shaft by reason of an excessive length of shaft extending between the gear box 14 and slack puller 19.

The above is considered to so fully reveal the gist of the invention that anyone studying the principles of its operation and the construction described may reproduce the same. That which is considered new, novel and useful and which is sought to be protected by Letters Patent of the United States is as follows:

I claim:

1. In a portable hoist; a platform; a cable reel adapted for rotation and mounted on said platform; a boom mounted on said platform and having a sheave on its free end; a cable wound on said reel and extending over said boom sheave; a slack puller mounted on said boom adjacent the boom sheave, comprising a sheave, means to drive said sheave substantially synchronously with said reel which includes means extending longitudinally of said boom and driven from said reel, and also comprising a pivoted lever mounted on said boom and carrying an idler sheave, said cable passing over said idler; pressure fluid operated means connected to said pivoted lever to move the cable passing over said idler sheave into engagement with said slack puller sheave; and a valve means on said platform operatively connected to said pressure fluid operated means to remotely control said pressure fluid operated means.

2. In a portable hoist; a platform having a reel rotatably mounted thereon and a cable thereon; a boom pivotally mounted on said platform, said boom having a sheave on its free end over which said cable passes; a slack puller mounted on the boom substantially adjacent the boom sheave, said puller including a rotatably mounted sheave, means to rotate said sheave at a speed which is substantially that of the cable reel which includes means extending longitudinally of said boom and driven substantially synchronously with said reel, a pivoted lever on said slack puller rotatably supporting an idler sheave,

said cable passing over said idler sheave; means mounted on said boom to vertically actuate said lever to bring the cable passing over said lever sheave into engagement with said slack puller sheave to thereby take up the slack in the cable as it is unwound from said reel; and a controller to govern said last mentioned means mounted on said platform.

3. In a portable hoist; a platform supporting a winding reel; a boom pivoted to said platform and having a sheave rotatably mounted at one end thereof; a cable on said reel and passing over said sheave; means on said boom to take up slack in said cable as it is unwound and mounted substantially adjacent said boom sheave including, a sheave rotatably mounted on said means, electric motor means to drive said sheave at a speed substantially that of said reel, a pivoted lever rotatably supporting an idler sheave on said means to take up slack and over which said cable passes; pressure fluid means connected to said lever to vertically move said idler to bring said cable in contact with said rotatably mounted sheave, whereby any slack in said cable is taken up as it is unwound from said reel; and a valve mounted on said platform to govern the actuation of said pressure fluid means.

4. In a material handling device; an operating deck; a boom pivotally secured to said deck and having a sheave at its free end; a cable winding device; a cable on said device which passes over said sheave; a slack puller mounted on the boom substantially adjacent said boom sheave, which includes a driven sheave and a movable idler sheave, said cable passing over said idler sheave, and means to move said idler sheave toward said driven sheave to bring said cable in contact with said driven sheave; means to rotate said driven sheave including a shaft extending longitudinally of said boom; means to rotate said shaft, said means being mechanically linked to said cable winding device; said winding reel and said driven sheave being rotated at speeds such that the cable between said winding device and said sheave will be in tension; and a controller mounted on said deck for governing said means to move said idler sheave to selectively bring said cable in contact with said driven sheave.

5. In a device of the character described; a platform; a cable drum rotatably mounted on said platform; a boom tiltably mounted on said platform; a sheave rotatably mounted on the free end of said boom; a cable wound on said

drum and passing over said sheave; means near the free end of said boom adapted to positively pass said cable over said sheave as it is unwound from said drum, said means including a driven sheave and an idling sheave mounted for movement relative of each other, said cable running over said idling sheave; means extending longitudinally of said boom and operatively connected to said drum to drive said driven sheave; means to relatively move said idling sheave and said driven sheave to bring said cable against said driven sheave; and a controller for said last mentioned means mounted on said platform to govern the relative movement of said idling and said driven sheaves.

6. In a portable crane device; a platform having a drum rotatably mounted thereon; a boom tiltably supported on said platform and having a sheave rotatably mounted on its free end; a cable throwout device mounted adjacent the free end of said boom, including a driven sheave and an idler sheave mounted for movement towards and away from said driven sheave; means to drive said driven sheave from said drum and extending longitudinally of said boom; means to control the application of said throwout device to a cable extending from said drum to and over said boom sheave including a pressure fluid device to move said idler sheave toward said driven sheave, said cable passing over said idler sheave; and a valve for said pressure fluid device mounted on said platform to govern the admission of pressure fluid to said device and bring said cable into contact with said driven sheave.

7. In a crane device; a platform; a drum adapted for rotation and mounted on said platform; a boom tiltably mounted on said platform; a sheave on the free end of said boom; a cable wound on said drum and having one end led over said sheave; a cable throwout device, including a driven sheave and an idler sheave relatively movable, mounted adjacent said boom sheave, said cable passing over said idler sheave; means to drive said driven sheave comprising a shaft extending longitudinally of said boom; gear means connecting said drum to said shaft; gear means connecting said shaft and said driven sheave; a pressure fluid system to relatively move said idler sheave and said driven sheave to bring said cable into contact with said driven sheave; and a control means for said system including a valve mounted on said platform to govern the admission of pressure fluid to said system.

FRED L. WHITE.
